UNITED STATES PATENT OFFICE.

WILLIAM C. HEDGCOCK, OF CHICAGO, ILLINOIS, ASSIGNOR TO AMERICAN STEEL
FOUNDRIES, OF NEW YORK, N. Y., A CORPORATION OF NEW JERSEY.

CLASP-BRAKE.

1,223,973.

Specification of Letters Patent. Patented Apr. 24, 1917.

Application filed October 2, 1916. Serial No. 123,258.

To all whom it may concern:

Be it known that I, WILLIAM C. HEDGCOCK, a citizen of the United States, and resident of Chicago, in the county of Cook 5 and State of Illinois, have invented certain new and useful Improvements in Clasp-Brakes, of which the following is a specification.

My invention relates to railway car brakes and has particular reference to an improvement or modification in the construction shown in my copending application, Serial No. 81,598, filed March 2, 1916, renewed Feb. 19, 1917, under Serial No. 149,656.

15 In the application referred to a construction was disclosed, in which two complete sets of brake riggings were provided, one at each side of the car, the brake levers of the rigging being connected to brake beams or bars near the ends thereof, the beams or bars carrying a brake head at their extremities. The present improvement relates 20 to a construction in which the location and arrangement of the brake riggings and the supports therefor are the same, but in which the brake heads are mounted upon brake hangers, the lower ends of the brake hangers serving as a point of connection for the brake bars or beams. In a construction such 25 as last described all the advantages accruing to the construction shown in the copending application heretofore referred to are present and in addition there is the advantage that the brake heads may be located at a 30 point nearer a horizontal line passing through the car axle. This is possible because of the location of the head at a point midway the length of the brake hanger.

The invention will be more readily understood by reference to the drawings in which the figure is a fragmentary perspective view illustrating a complete rigging, the points of connection to the truck being omitted.

By referring to the figure, it will be seen 45 that I have illustrated a rigging adapted for six-wheel trucks, the brake being of the clasp type; that is, the type in which two brake shoes are applied to each wheel.

The air cylinder pull rods are indicated 50 at 10, the ends of the rods connecting with the brake levers 11. The lower ends of the brake levers 11 connect with brake bars 12 near the ends of the bars. Pivoted to the ends of the bar 12 are hanger levers 13, 55 the upper ends of which are connected at

14 to a rigid portion of the truck. A brake head and shoe 15 are connected to the hanger lever at a point intermediate the ends thereof. The bar or beam 12 serves the double function of connecting the two 60 sets of rigging and supporting both sets of rigging on a line along the longitudinal center line of the truck at a single point at the center and also by the hanger levers 13, at both sides of the truck. The single point 65 supporting means comprises the hanger 16, connected at its upper end to the bracket 17, which is secured to a portion of the car truck.

The rigging just described is connected by 70 links 18, 19, to other units of the same character, the last brake lever 20 being anchored at 21 to a rigid portion of the truck. The riggings are duplicated on each side of the truck. The novelty in the present construction over that of my copending application referred to is in the mounting of the brake head upon the hanger levers instead of on the ends of the beam.

Undoubtedly other modifications will suggest themselves to those skilled in the art, and I do not, therefore, wish to be limited to the exact form shown and described.

I claim:

1. In a brake, the combination of a complete set of brake rigging at each side of the truck, said rigging including a hanger lever and a brake shoe attached thereto at a point intermediate the ends thereof, a beam connecting the riggings at each side of the truck and pivoted at the lower ends of said hanger levers, and a middle support for said beam, substantially as described. 85

2. In a clasp brake, the combination of riggings, located one at each side of the truck, a hanger lever, the upper end of which is pivoted to the truck, a brake head secured to said hanger lever intermediate the ends thereof, a brake bar pivoted to the lower end of said hanger lever and serving 95 to connect the riggings on the two sides of the truck, and a support, in the form of a bracket and link, connected to said brake bar near the middle thereof, substantially as described. 100

3. In a clasp brake for trucks, the combination of a pair of riggings, one at each side of the truck, brake bars connected to said riggings, hanger levers depending from the truck in the plane of the wheels, brake heads 110

secured to said levers intermeditae the ends thereof, the lower ends of said hanger levers being pivoted to said brake bars, and a support for each of said brake bars, said supports being located on the longitudinal center line of the truck, substantially as described.

Signed at Chicago, Illinois, this 27th day of September, 1916.

WILLIAM C. HEDGCOCK.
